UNITED STATES PATENT OFFICE.

WILLIAM BARTHOLOMEW, OF CHICAGO, ILLINOIS.

DRY-ROOM HANGER.

No. 924,722.

Specification of Letters Patent.

Patented June 15, 1909.

Application filed January 11, 1909. Serial No. 471,669.

To all whom it may concern:

Be it known that I, WILLIAM BARTHOLOMEW, citizen of the United States, residing at Chicago, county of Cook, and State of Illinois, have invented certain new and useful Improvements in Dry-Room Hangers, of which the following is a specification, reference being had therein to the accompanying drawing.

10 This invention relates to a dry room hanger, and particularly to a structure adapted to form part of an endless carrier from which the goods may be automatically released at any desired point in its travel.

15 The invention has for an object to provide a novel and improved construction of yoke having a goods supporting face in connection with an angular gripping lever pivoted upon the yoke and having a coöperating gripping face and a releasing arm extended upward from the face of said lever.

20 Other and further objects and advantages of the invention will be hereinafter fully set forth and the novel features thereof defined 25 by the appended claims.

In the drawings:—Figure 1 is a front elevation of the invention with the carrier track in section; Fig. 2 is a side elevation thereof; Fig. 3 is a perspective view of the 30 gripping lever; Fig. 4 is a detail perspective of the yoke; and Fig. 5 is a plan of the releasing plates.

Like numerals refer to like parts in the several views of the drawing.

35 The numeral 10 designates the shank of the hanger which may be of any desired construction or configuration and is provided at its lower end with the cross bar 11 and intermediate of its ends with the link member 12 adapted to coöperate with the links of the carrier, as shown in Fig. 2. The upper end of the shank is provided with the carrier wheels 14 of any desired construction adapted to travel on the track or ways 15. The 40 cross bar 11 is provided with one or more yokes 16. In the form here shown these yokes are provided with a central depending plate 17 which may be formed with pivoting apertures 18 and spaced from this plate are 45 the depending arms 19 having inwardly curved free ends formed with laterally extending gripping faces 20, these faces being at the outer ends of the bar 11. Coöperating 50 with these faces is the angular gripping lever 21 which is pivoted at 22 in one of the 55

apertures 18 and formed with a laterally extending gripping face 23 at its outer end. The angular portion 24 of this lever extends upward and forms a releasing arm, the upper end 25 of which projects above the cross 60 bar and substantially parallel to the shank 10 of the hanger to be engaged by any suitable operating device. Extending laterally from the releasing arm 24 and at an angle thereto is the counterweight arm 26 which 65 also forms a guide as it travels in sliding contact with the depending arm 19 of the yoke. The extended gripping face 23 of this lever also acts as a stop to limit any upward swing of the lever by engaging the edge of the plate 17. 70

A desirable form of fixed means for operating either one or both of the gripping levers for releasing the goods comprises releasing plates or bars 27 having oppositely inclined faces 28. These plates may 75 be supported in any desired manner, for instance, by means of the hanger 29 extending from the track or way 15. The inclined face 28 of the releasing plates extends inward toward the shank of the hanger thus 80 throwing the gripping lever in that direction in the movement for releasing the goods.

In the operation of the invention it will be seen that the goods may be introduced into the grippers by simply pressing upward 85 upon the lever member or its counterweight arm and this member returns automatically to grip and hold the goods, the weight thereof acting to increase the gripping action, as the arc of travel of the gripping face of 90 the lever intersects the fixed gripping face upon the yoke. The counterweight arm effects an automatic return of the lever to its initial or closed position after it has passed the inclined face of the releasing 95 plate and also guides the movement of the lever in both directions. The laterally extending gripping face upon the lever will act as a stop to prevent the parts being thrown past the center so as to prevent 100 their return by gravity. The disposition of the releasing arm from the gripping lever extended upward above the cross bar and intermediate of the ends thereof permits the location of the releasing plates directly 105 adjacent to the shank of the hanger thus greatly economizing in the width of the structure by avoiding the use of releasing devices beyond the ends of the yokes. This is an important feature as it prevents inter- 110

ference by parallel lines of the carrier and also any contact with the goods held thereby. Furthermore, by moving the releasing arm toward and from the shank of the hanger 5 the same is steadied and supported in its travel so as to prevent any lateral displacement by the weight of the garment even if the portion held by one gripper be released prior to the other portion. As this releasing 10 plate is disposed adjacent to the point of introduction of fresh goods to be dried into the grippers which have been previously operated by the plate, the action of the plate upon the subsequent gripper arms 15 steadies the entire carrier chain and thereby facilitates the introduction of fresh goods thereto.

The invention presents a simple, efficient and economical form of dry room hanger in 20 which the gripping devices may be automatically opened to release the goods and exert a constant holding tension upon the goods therein.

Having described my invention and set 25 forth its merits, what I claim and desire to secure by Letters Patent is:—

1. In a dry room hanger, a yoke having a gripping face, a pivoted gripping lever having a coöperating gripping face, and a releasing 30 arm extended upward from the said lever to separate said faces for the automatic discharge of goods therefrom.

2. In a dry room hanger, a yoke having a gripping face, a pivoted gripping lever having a coöperating gripping face, a releasing arm extended in alinement with the face of 35 said lever, and a counterweight arm extended at an angle from the releasing arm.

3. In a dry room hanger, a yoke having 40 depending free ends one of which is provided with a laterally extended gripping face, a gripping lever pivoted upon the opposite end and having a coöperating laterally extended gripping face, and a releasing arm extended 45 in alinement with said face.

4. In a dry room hanger, a yoke having depending free ends one of which is provided 50 with a laterally extended gripping face, a gripping lever pivoted upon the opposite end and having a coöperating laterally extended gripping face, a releasing arm extended in alinement with said face, and a counterweight arm upon said lever extended from the releasing arm in contact with the yoke 55 upon which the lever is pivoted.

5. In a dry room hanger, a yoke having a gripping face, a pivoted gripping lever having a coöperating gripping face, a releasing arm extended in alinement with the face of 60 said lever, and a releasing plate having an inclined face adapted to engage one side of said releasing arm.

6. The combination with a track, of a traveling conveyer supported thereon, a shank 65 depending from said conveyer and

provided with a cross piece at its lower end, gripping devices upon said cross piece each comprising a yoke having a gripping face adjacent the end of the cross piece, a gripping lever provided with a coöperating face, and a releasing arm extended in alinement with 70 said face upwardly above the cross piece.

7. The combination with a track, of a traveling conveyer supported thereon, a shank depending from said conveyer and provided 75 with a cross piece at its lower end, gripping devices upon said cross piece each comprising a yoke having a gripping face adjacent the end of the cross piece, a gripping lever provided with a coöperating face, a releasing 80 arm extended in alinement with said face upward above the cross piece, and a hanger provided with means for moving said releasing arm toward said shank.

8. In a dry room hanger, a supporting 85 member having a cross piece extended laterally at the opposite sides thereof, a gripping device comprising yokes secured to said cross piece and provided with gripping faces, and an angular lever pivoted upon each of 90 said yokes and formed with a coöperating gripping face at its angle and a releasing arm extended upward therefrom.

9. In a dry room hanger, a gripping device comprising a U-shaped yoke having a central 95 pivoting plate and spaced gripping arms at opposite sides thereof, and levers pivoted on said plate and having at one side thereof a gripping face to coöperate with that of the yoke and a releasing arm extended from said 100 gripping face.

10. In a dry room hanger, a gripping device comprising a U-shaped yoke having a central pivoting plate and spaced gripping arms at opposite sides thereof, levers pivoted 105 on said plate and having at one side thereof a gripping face to coöperate with that of the yoke and a releasing arm extended from said gripping face, and a counterweight arm extended at an angle from said releasing arms. 110

11. In a dry room hanger, a yoke having a gripping face, an angular gripping lever pivoted opposite the gripping face of the yoke and having a gripping face at the angle thereof. 115

12. In a dry room hanger, the combination with the shank and cross bar at the lower end thereof, of a yoke carried by said bar and having a gripping face, and a pivoted lever having a coöperating gripping face and a releasing arm extended upward above said cross bar and substantially parallel to the shank of the hanger. 120

13. In a dry room hanger, the combination with the shank and cross bar at the lower end thereof, of a yoke carried by said bar and having a gripping face, a pivoted lever having a coöperating gripping face and a releasing arm extended upward above said cross bar and substantially parallel to the shank of 125 130

the hanger, and means for automatically moving said arm toward and from said hanger.

14. In a dry room hanger, a yoke comprising a central depending plate and depending arms at the opposite ends of the yoke spaced from said plate, a gripping face upon one of said parts, and a coöperating gripping lever pivoted upon the opposite part.

10 15. In a dry room hanger, the combination with the shank and cross bar thereof, of a yoke disposed at opposite sides of said shank

and provided with gripping faces, gripping levers pivoted to said yoke and having releasing arms extending upward at each side 15 of said shank, and a releasing plate having an inclined face disposed to engage a side of said arms.

In testimony whereof I affix my signature in presence of two witnesses.

WILLIAM BARTHOLOMEW.
